UNITED STATES PATENT OFFICE.

CHARLES KLAUBERG, OF NEW YORK, N. Y.

BOTTLE-HOLDER.

1,239,109.

Specification of Letters Patent. Patented Sept. 4, 1917.

Application filed October 18, 1916. Serial No. 126,273.

To all whom it may concern:

Be it known that I, CHARLES KLAUBERG, a citizen of the United States, residing at New York, in the county and State of New York, having invented certain new and useful Improvements in Bottle-Holders, of which the following is a full, clear, and exact specification.

This invention relates to bottle holders and especially to devices for holding nursing bottles for babies in position for the baby to be fed therefrom, or in inoperative position so that the milk will not be spilled therefrom.

15 A special object is to provide a holder of this kind which may be folded into compact form for transportation and which may be quickly set up into position for holding the bottle when desired. Other objects will 20 appear as the description proceeds.

The invention will be first hereinafter described in connection with the accompanying drawings, which constitute part of this specification, and then more specifically defined in the claims at the end of the description.

25 In the accompanying drawings, wherein similar reference characters are used to designate corresponding parts throughout the 30 several views:

Figure 1 is a perspective view of the preferred embodiment of the invention applied to a bottle in operative position.

Fig. 2 is a similar view in inoperative position, and

Fig. 3 is a plan view of the holder in folded position.

The bottle holder is made of wire of any suitable or desired cross-section, and consists of two parts or frame members 2 and 3 hinged together to permit them to be arranged in the relative position shown in Figs. 1 and 2 when used for holding a bottle 1, and to also be folded into the same plane, 45 as illustrated in Fig. 3, for more conveniently carrying the holder when not in use. The frame 2 comprises essentially a ring 4 at the upper ends of angularly bent portions 5 at the opposite end of said frame 50 from that to which the frame 3 is hinged. In making the frame 2 a single piece of wire is preferably used, the same being coiled to form the ring 4 and the end portions of the wire bent to form the portions 55 5 as well as the spaced side portions 2^a of the frame. The extremities of said side por-

tions 2^a are bent to form eyes 6 by means of which the frame 3 is hinged to the frame 2.

The frame 3 comprises essentially a pair of resilient gripping arms 8 adapted to engage the body of the bottle 1, and a loop 7 with which the eyes 6 are connected to form the hinge joint. In making the frame 3 of a single piece of wire, which is preferred, the middle portion of the wire is 65 bent upon itself to form the loop 7, and the end portions of the wire are crossed and curved, as at 9, to fit around the bottle. The extremities of this wire may be turned over, as at 10, to give them a better finish. 70

As shown in Fig. 1, when the frame 3 is arranged substantially parallel to the ring 4, the neck of the bottle 1 may be inserted in said ring and the body portion of the bottle placed between the resilient arms 8 75 and said bottle supported in operative position upon the body portion of the frame 2. The holder is also adapted to support the bottle in inoperative position, as illustrated in Fig. 2, the eyes 6 and bottom of the bottle 80 being the points of support in this instance. When the support is not in use the frame 3 with the arms 8 may be folded into the plane of the body portion of the frame 2, as illustrated in Fig. 3, thereby making the 85 device much more convenient to carry than would be possible if it were made in a single rigid piece. Another important advantage in the present construction is that the two frames may be more cheaply buffed separately after being plated because of the accessibility of the parts. Before the two frames are connected together, the eyes 6 90 may be opened, as indicated in dotted lines in Figs. 1 and 2, and after buffing the loop 95 7 may be placed in the eyes and said eyes closed, as shown in solid lines.

Having thus described my invention, what I claim as new and desire to secure by Letters Patent of the United States is:— 100

1. A bottle holder comprising two frames hinged together and adapted to be folded upon one another when not in use, each frame having means for holding a bottle, the means of one frame being resilient and 105 opening at one side to permit the body of the bottle to be inserted and withdrawn.

2. A bottle holder comprising two frames hinged together and adapted to be folded upon one another when not in use, one frame 110 having a ring to engage the neck of a bottle and the other frame having a pair of re-

silient arms for gripping the body of the bottle.

3. A bottle holder comprising two frames of wire, each frame having bottle engaging means, one frame having eyes formed in the wire at one end, and the other frame having a loop pivotally connected to said eyes, whereby one frame may be folded upon the other when the holder is not in use.

4. A bottle holder comprising two frames, each made of a single piece of wire, one frame having the middle portion of the wire bent to form a loop and the ends to form resilient bottle gripping arms, the other frame having the middle portion of the wire coiled to form a ring to encircle the neck of the bottle, and the extremities of said wire being bent to form eyes pivotally connected to the loop of the first frame.

5. A bottle holder comprising two frames hinged together, one frame having a loop and means for engaging the body of a bottle, the other frame having a ring for encircling the neck of the bottle and eyes connected to the loop of the first frame to form the hinge, whereby one frame may be folded upon the other when the holder is not in use.

6. A bottle holder comprising two frames of wire hinged together and adapted to be folded one upon the other when not in use, one frame having a pair of gripping arms, and the other frame having spaced side portions between which said arms are adapted to lie when the holder is folded.

In testimony whereof I have signed my name to this specification.

CHARLES KLAUBERG.
